UNITED STATES PATENT OFFICE.

ANDREW BELL, OF MANCHESTER, COUNTY OF LANCASTER, ENGLAND.

WATER-FILTER.

SPECIFICATION forming part of Letters Patent No. 252,718, dated January 24, 1882.

Application filed July 5, 1881. (Model.)

To all whom it may concern:

Be it known that I, ANDREW BELL, a subject of the Queen of Great Britain and Ireland, and residing at Manchester, county of Lancaster, England, have invented certain Improvements in Water-Filters, of which the following is a specification.

The object of my invention is to produce a rapid water-filter, combining efficiency of action and facility for cleansing with lowness of cost. I charge a reversible chamber with filtering media, and I employ a screw to compress the filtering media and also to tighten the joints between the chamber and the base and cover of the same. The said screw engages with a bridle which is hinged to the base, and acts upon the upper one of two grids, between which the filtering media are compressed.

In the accompanying drawings, Figure 1 represents a vertical section of the filter; and Fig. 2 is a curtailed outside view, showing the connection of the bridle with the base.

In Fig. 1, *a* is the chamber, *b* is the cover, *c* is the base, *d* is the screw, and *e* is the bridle. The chamber consists of a cylinder open at both ends and entering annular grooves formed in the cap and base. The base *c* is formed with an inlet-passage, *f*, for unfiltered water, and is provided with an outlet-tap, *g*, for unfiltered water. If it is not considered to be necessary to provide for the drawing of unfiltered water through the base, the tap *g* may be dispensed with. A recess is formed in the base, and over this recess is placed a perforated disk or grid, *h*. The space above this grid is filled with the filtering media, and a second grid, *i*, is placed on the top of the filling. In practice I use silicate-cotton, otherwise termed "slag-wool," and animal-charcoal, a layer, *k*, of the former being first placed at the bottom of the chamber, which is then nearly filled with granulated or coarsely-powdered animal-charcoal. (Represented by the darker portion of the filling.) A second layer, *l*, of silicate-cotton is placed on the top of the charcoal, and the grid *i* is placed in position.

The bridle *e* is formed at each end with a hook, and each hook engages with a stud, *m*, which is cast on the base, as indicated by the dotted lines, and as shown in Fig. 2. In the center of the upper part of the bridle a hole is

drilled or formed, and is tapped to suit the screw. When the chamber is charged with filtering media the cover is placed in position, and the bridle is hooked onto the studs and is turned up into a vertical position. The screw can then be screwed downward by turning the key or handle *n*, so that the end of the screw passes through a hole in the cover and bears upon the center of the grid *i*. The said grid can thus be forced downward by means of the screw, so as to compress the filtering media to any desirable extent, the filtering action increasing in effect, but losing in rapidity, with an increase in the compression of the media. Rings of vulcanized caoutchouc are placed in the grooves in the cover and base, and the two ends of the chamber bed upon these rings. A wing nut, *o*, is tapped to suit the screw, and when the filtering media have been sufficiently compressed this nut is screwed tightly down upon the cover, whereby the joints at the two ends of the chamber are tightened, so as to prevent the escape of water. The bridle *e*, with its screw, thus forms the means for keeping the parts of the filter together, and at the same time for compressing the filtering material.

A leather, lead, or tin washer may be interposed between the cover and the nut *o*; or the joint may be faced or packed or otherwise rendered suitably tight.

The inlet *f* is coupled or connected in any ordinary or suitable manner with the water-supply pipe.

The cover is provided with an outlet-tap, *p*, and when this tap is opened the water flows through the grids and the filtering media, and is received in a filtered condition from the tap. When the tap *g* is opened any dirt which has collected in the recess in the base is carried out by the flow of water.

When it is considered to be desirable to cleanse the filter the nut *o* is slackened and the screw is turned until the bridle can be turned back so that the cover can be lifted off. The chamber is then lifted off the base, inverted, and replaced, so that the end which was the inlet end of the chamber will be the outlet. The cover is then replaced and is tightened up by means of the nut; but the screw is not turned sufficiently to compress the filtering media. The water is then allowed to flow through the

media while they are free from compression, and as the water flows in a contrary direction to the previous flow it carries off the impurities from the upper end of the filter. When 5 the water runs quite clear the nut *o* is slackened and the screw is turned to compress the filtering media. As the silicate-cotton is a mineral and is not subject to decomposition, I consider it to be very suitable for the purpose; 10 but any suitable medium or media may be substituted for it or for the animal-charcoal.

The chamber may be otherwise than cylindrical in form; but I prefer that form, as I can produce the chambers at a low cost by cutting 15 up a cast-iron pipe into lengths.

I claim—

1. The combination of the cylinder *a*, adapted to receive filtering media, and the cover and base with a bridle, *c*, hinged to the base, a 20 screw, *d*, and nut *o*, all substantially as described.

2. The combination of the filtering-cylinder, cover, base, and movable grids between which the filtering media are contained, with a bridle connected to the base, a screw bearing on one 25 of the grids, and a nut on the screw adapted to bear on the cover, all substantially as set forth.

3. The combination of the cover and the recessed base, one having an inlet and the other 30 an outlet, with a reversible cylinder containing filtering media and loose grids, the lower one adapted to rest on the base, substantially as specified.

In testimony whereof I have signed my name 35 to this specification in the presence of two subscribing witnesses.

ANDREW BELL.
